UNITED STATES PATENT OFFICE.

JOSEPH P. MAXFIELD, OF MILLBURN, NEW JERSEY, ASSIGNOR TO WESTERN ELECTRIC COMPANY, INCORPORATED, OF NEW YORK, N. Y., A CORPORATION OF NEW YORK.

ACOUSTICAL AID FOR DEAF PERSONS.

Application filed September 28, 1921. Serial No. 503,771

To all whom it may concern:

Be it known that I, JOSEPH P. MAXFIELD, a citizen of the United States, residing at Millburn, in the county of Essex, State of New Jersey, have invented certain new and useful Improvements in Acoustical Aids for Deaf Persons, of which the following is a full, clear, concise, and exact description.

This invention relates to a device for improving the hearing of persons whose audition is subnormal.

It has been observed that in some cases of defective hearing, the persons so affected can more readily distinguish ordinary sounds when there are present sounds having certain periods of vibration. These superimposed vibrations serve, it seems, to agitate the inner ears and render them more receptive to the sounds which it is desired to hear. It is possible therefore to improve the hearing in such cases by deliberately introducing in the receivers of a deaf set sounds having the proper frequency components to agitate the ears. The frequency of such sounds vary for different purposes and should be selected to suit the individual. Such sounds may or may not be within the audible range of the person employing the device.

An object of the invention is to provide means for agitating the organs of hearing in order to make them more receptive to sounds which it is desired to hear.

Other objects will hereinafter appear.

Referring to the drawings:

Fig. 1 represents a binaural system embodying the invention.

Fig. 2 represents another method of introducing the auxiliary sounds.

In general the invention consists in providing microphones inductively connected to the input side of amplifiers, receivers connected to the output side, and means in the receiver circuit for introducing in the receivers auxiliary sounds.

In Fig. 1, two microphones 4 and 5 are connected in series with batteries 6 and 7 and the primary windings of induction coils 8 and 9 respectively. Secondary windings 50 of the induction coils 8 and 9 are connected to the terminals of the resistances 10 and 11 which in turn are bridged across the input circuits of two vacuum tube amplifiers 12 and 13 having the usual heated cathodes 14 and 15, control electrodes 16 and 17, and

anodes 18 and 19. The temperature of the filaments and consequently the output of the amplifiers can be readily adjusted by means of rheostats 20 and 21 located in the filament circuits. The output circuits of the amplifiers 12 and 13 are connected respectively to primary windings of transformers 22 and 23. The secondary windings of these transformers are connected through the secondary windings of transformer 26 to receivers 24 and 25. Across the primary of transformer 26 is connected a source of varying current 27 in any convenient form such as a vacuum tube oscillator. The frequency of the oscillator may be adjusted in any well known manner to the frequency most advantageous for exciting the ears of the person employing the system.

In Fig. 2 the source 27, in series with a condenser 28, is bridged across receivers 24 and 25 in series.

Although a binaural system for deaf persons has been chosen to illustrate the invention, it is obvious that the invention may be applied to systems designed for one ear only. Again, the system may involve the excitation of the sense of hearing without the use of head receivers, as in cases where the deaf person may be located within the range of influence of the exciting energy. The specific form which the invention may take is dependent upon the character of the deafness and the frequencies of the sounds or energy required to stimulate the sense of hearing of the person using it.

What is claimed is:

1. The method of improving the hearing of a deaf person, which consists in generating continuous vibrations, applying said vibrations to the patient simultaneously with the sound vibrations to be heard, and adjusting the frequency of the continuously generated vibrations to suit the individual case.

2. In a binaural system for enabling deaf persons to hear, a pair of microphones, amplifiers associated with said microphones, a pair of receivers associated with said amplifiers, and common means connected between each receiver and each amplifier for introducing a varying current in the receivers.

3. In a system for enabling deaf persons to hear, a pair of microphones, an amplifier associated with each of said microphones, a pair of receivers associated with said amplifiers, and means connected between each re-

ceiver and each amplifier for introducing a varying current into the receivers, said means common to both receivers.

4. The method of aiding a deaf person to perceive sounds with naturalness, comprising separately amplifying the sound occurring at two points separated in space, separately applying the amplified sounds to

the two ears of the patient, and simultaneously applying to the two ears continuous vibration of such frequency as to aid the patient to hear said sounds.

In witness whereof, I hereunto subscribe my name this 24th day of September A. D., 1921.

JOSEPH P. MAXFIELD.
